SHOE

James Blaine Cort, Irvington, N. J.

Application May 23, 1939, Serial No. 275,136

1 Claim. (Cl. 36—3)

This invention relates to the manufacture of shoes and particularly to improvements whereby the soles of shoes are made flexible so that no "breaking in" is necessary before the shoe is comfortable to the foot.

The invention is applicable to all types of shoes and slippers in which inner and outer soles are employed, whether made by the Goodyear welt, Little-way, McKay, cement, or other known process. The advantages of the invention may be secured regardless of the thickness of the inner sole in any of these types of shoes.

In shoes of the kind described, the inner sole consists of a continuous strip of leather or substitute therefor, to which the upper is secured. The outer sole may be of leather, composition, rubber or other material. The two layers, secured together, stiffen the bottom of the shoe so that in the experience of most wearers the shoe is not comfortable until it has been flexed by wear sufficiently to reduce this stiffness materially. Often the shoe is half worn out before the sole is sufficiently flexible for comfort.

It is the object of the present invention to provide a method of making shoes and an improved insole for shoes whereby the completed shoe has an initial flexibility which makes it comfortable to the wearer immediately.

Another object of the invention is the provision of a shoe structure which avoids cracking of the insole due to perspiration and in which the insole is capable of movement relative to the outsole, affording thereby a healthy massaging effect on the palm of the foot.

Other objects and advantages of the invention will be apparent as it is better understood by reference to the following specification and the accompanying drawing, illustrating the preferred embodiments of the invention, in which

Fig. 1 is a sectional view showing the inner and outer soles and a portion of the upper to indicate the relation of these parts, it being understood, however, that the outer sole need not be secured by a welt and that the upper may be secured to the insole otherwise than as shown;

Fig. 2 is a bottom plan view illustrating a portion of an insole embodying the invention;

Fig. 3 is a section on the line 3—3 of Fig. 2;

Fig. 4 is a section on the line 4—4 of Fig. 2; and

Fig. 5 is a view similar to Fig. 4 illustrating the application of strengthening canvas to the lip of the insole.

The invention may be applied to all types of insoles including so-called "Economy," "Gem," and "shoulder" insoles, and also plain insoles in

which there is no channeling. It will be described more particularly with reference to the manufacture of a typical shoe, but it is understood that the invention is not limited to this type.

In carrying out the invention, I provide an insole, preferably of leather, suitably shaped and sized. A plurality of parallel transverse slots are provided in the insole, preferably with transverse slits interposed. The first slot is disposed substantially at the break of the ball, and the slots and slits are spaced about $\frac{1}{8}$ inch apart, to within about one inch of the toe. The slots are preferably about $\frac{1}{2}$ inch in width and extend across the shoe to substantially the edges of the channel, if one is used, otherwise to approximately the same points. The slits are merely cuts in the insole parallel to the slots. The spacing and the width of the slots may be varied, but the dimensions noted are best adapted to accomplish my purpose.

The provision of narrow slots and the additional slits, if the latter are used, affords in the insole a degree of flexibility at the section of the sole where the shoe is flexed in walking. When the outer sole is secured, if cement is used, it is applied only around the outer edges, leaving the inner space free so that relative movement between the inner and outer soles is possible. Instead of stiffening the outer sole as is usual in shoes as heretofore constructed, the inner sole is substantially free and flexible, and consequently the outer sole bends without restraint, thus giving to the shoe an initial flexibility which heretofore has not been possible.

In the accompanying drawing, I have illustrated the application of the invention to a typical shoe construction, with the understanding that the details other than the provision of slots to afford flexibility are not essential. Referring to the drawing, 5 indicates a portion of the outer sole extending to the shank 6, and 7 indicates the inner sole which is channeled to afford a lip 8 to which the upper 9 is secured. The inner and outer soles are held together by stitching 10 extending through the lip 8 and the lower edge of the upper, and stitching 10' extending through the welt 11 and the outer sole.

The inner sole 7, in accordance with the invention, is provided with a plurality of parallel transverse slots 12 and interposed slits 13 spaced between the ball and the toe.

In manufacturing the shoe, the insole 7 in this particular type is channeled at 14, and the portions of leather cut away from the body thereof

are drawn upwardly and cemented to form a lip 8 to which the upper of the shoe is secured by stitching. The insole is also subjected to the action of a die to cut the slots 12 and the slits 13 therein, as indicated in Fig. 2.

If the insole is of relatively thin material, it may be necessary to reinforce the lip. For this purpose, canvas may be cemented onto the under face of the insole and about the inner face of the lip. The insole is then tacked upon the last, and the manufacture of the shoe proceeds in accordance with the regular practice. After the shoe has been sewed or in-seamed, the canvas is cut from the main portion of the insole close to the stitches and, except for the part 15 thereof cemented to lip 8, is removed entirely to expose the inner surface of the insole and the slots therein, as indicated in Fig. 1. Where filling is required in the channel of the insole, the filling is applied only at the channel.

If the shoe is of the Goodyear welt type, as shown in Fig. 1, the outsole is cemented only around the welt and in-seam of the shoe, and the center of the outsole and insole are left free so that they may move relatively during the flexing of the shoe. In making shoes, where shoulder insoles are used, it is not necessary to use canvas to reinforce the lip. In making shoes by the Little-way, McKay or cement process, or in

the manufacture of slippers where extremely light-weight insoles are used, no channeling is required. Hence, as indicated above, the invention is independent of such steps as channeling and other details of the manufacture of shoes, and depends upon the provision of an insole having transverse slots, with or without the addition of slits interposed between the slots, to afford flexibility in the finished shoe. 5

Various changes may be made, therefore, in the application of the invention without departing from the essential feature thereof.

I claim:

A shoe having an outsole and an insole, the insole having a slotted region extending approximately from the break line of the shoe to the toe portion thereof, said insole being secured to the outsole at the sides thereof opposite said slotted region but being not secured to the outsole at said slotted region, the slots in said region extending 20 entirely through the insole and extending continuously in the same general direction and in generally parallel relation, in a direction substantially normal to the longitudinal center of the shoe, from the portion of the insole at one 25 side thereof which is attached to the upper to the portion thereof at the other side which is attached to the upper.

JAMES BLAINE CORT.
